ATTORNEY.

UNITED STATES PATENT OFFICE.

HARRY BARRINGER COX, OF HARTFORD, CONNECTICUT.

THERMO-ELECTRIC GENERATOR.

SPECIFICATION forming part of Letters Patent No. 518,542, dated April 17, 1894.

Application filed April 28, 1892. Renewed February 2, 1893. Again renewed October 6, 1893. Serial No. 487,394. (No model.)

To all whom it may concern:

Be it known that I, HARRY BARRINGER COX, of Hartford, in the county of Hartford and State of Connecticut, have invented certain new and useful Improvements in Thermo-Electric Generators; and I do hereby declare that the following is a full, clear, and exact description of the invention, which will enable others skilled in the art to which it appertains to make and use the same, reference being had to the accompanying drawings, and to the letters of reference marked thereon, which form part of this specification.

This invention relates to certain improvements in thermo electric generators.

The object of the invention is to improve certain details in the arrangements, constructions and operation of certain parts whereby the durability and effectiveness of the apparatus is greatly increased and the utility and advantages thereof broadened.

A further object of the invention is to provide certain improvements in the construction and manufacture of thermo electric generators whereby a superior and more durable machine is produced which will not be injured and soon worn out by the intense heat and the cold to which the machine is subjected.

The invention consists in certain novel features of construction and in combinations of parts more fully described hereinafter and particularly pointed out in the claims, and the invention further consists in certain improvements in the manufacture of thermo electric generators.

Referring to the accompanying drawings:— Figure 1 is a vertical sectional view of the completed apparatus. Fig. 2 is a detail view.

Heretofore thermo electric generators have been constructed as upward extensions of a fire pot or heating means. The inner faces of the series of rings or sections composed of thermo couples were provided with a fire proof corrugated coating to withstand the intense heat; the outer face of the pile having been coated with water proof material, such as paint and surrounded by a water jacket.

By practical experience it has been found that a mere water proof paint in the present

state of the art will not suffice for the outer covering of the pile.

The object of my invention is to obviate so far as possible all defects in construction and operation of the thermo electric generator as above described.

The pile is built up of a series of rings or sections *a*. Each section is composed of a series of thermo couples connected together in any suitable manner as will be readily understood by those skilled in the art. The various sections are suitably connected to connect the entire pile in the circuit, and *b*, *b*, indicate the binding posts connected, respectively, preferably, by insulated wires *b'* with opposite poles of the pile.

In carrying out the present invention a pile is formed of the sections of couples separated by suitable insulating material *c*. The sections are suitably held together and the outer and inner faces thereof are coated with cement or fire clay or other suitable refractory material *d*, and baked hard. The pile is then like a hard stone structure. The ends and outer face of the cylinder are then preferably smoothed off and treated with some suitable substance, such as plumbago, and the open ends of the structure are temporarily closed and the exterior and ends of the same are coated with a metal jacket *e*, by electro plating. The metal jacket *e*, is preferably confined to the exterior and ends of the pile, but if desirable the entire pile or structure can be coated with metal. While electro-plating at present appears to be the most practical way of providing the metal jacket still it is obvious that a thin sheet metal jacket might be wrapped around the outer wall and the edges soldered, brazed or otherwise fastened and the ends headed over. If a very close fit is desired the metal jacket can be placed on while the cement or clay is yet soft.

To render the cement or refractory coating impervious to moisture it is coated with wax or suitable varnish. This non conducting surface is rendered a conductor by the plumbago coating.

f f' indicate the flanged end pieces, rings or heads between which and the ends of the pile the rubber gaskets or rings *g*, are clamped.

The fire pot *h*, at its lower end of the pile fits the flange of the lower end piece *f*, and is preferably provided with supports or standards. The upper end of the pile is provided with the hood *i*, mounted on the upper end piece *f'*. The outer jacket *j*, forms a water space around the pile and is fitted in and clamped between the end pieces *f f'*, and the two end pieces and outer jacket are clamped in position by the bolts *k*, passing through the end pieces and water space, whereby all the parts are clamped together.

l, indicates the deflectors suspended in the upper part of the pile to distribute the heat.

15 *m, m'* indicate the inlet and outlet pipes through the opposite end pieces.

It is evident that various changes might be resorted to in the form, construction and arrangement of the parts described without departing from the spirit and scope of my invention hence I do not wish to limit myself to the precise construction here disclosed.

Having thus fully described my invention, what I claim, and desire to secure by Letters 25 Patent of the United States, is—

1. The herein described mode of constructing thermo electric generators which consists in connecting and arranging the thermo couples to form the pile, coating the same with fire proof material, such as cement or clay, and then hardening or baking the same, and then placing a metallic jacket or coat on the pile by electro plating or other means on said fire proof coating, substantially as described.

35 2. The thermo electric pile having the ends of the couples coated with hardened fire proof material and provided with a metal jacket or coating, as and for the purpose set forth.

3. A thermo electric generator comprising the open pile arranged to be interiorly heated, the outer face thereof being coated with hard-

ened cement, clay or the like rendered water proof, and a water space surrounding the same, substantially as described.

4. In a thermo electric generator the open 45 pile coated externally and interiorly with hardened cement or clay and provided with an external metallic jacket, substantially as described.

5. In combination, a thermo pile coated with 50 hardened fire proof material, as clay or other substance, an exterior metal jacket extending over the ends thereof, a water jacket around the pile, end pieces, packing between the end pieces and ends of the pile, and means for 55 holding the end pieces together, substantially as described.

6. In a thermo electric generator, the combination of the open rigid pile, coated with refractory material the annular end pieces on the ends of the same, the water jacket clamped between said end pieces, and forming a water space around the outer surface of the pile the bolts uniting the same, the fire pot attached to the lower end piece and the hood 60 attached to the upper end piece, substantially as described.

7. A thermo electric pile having the closely fitted metallic jacket forming its outer surface, as and for the purpose set forth.

8. A thermo electric pile having its outer surface provided with a closely fitted metallic jacket, and refractory material between said jacket and the ends of the thermo electric elements, substantially as described.

In testimony that I claim the foregoing as my own I affix my signature in presence of two witnesses.

HARRY BARRINGER COX.
